LISTING MECHANISM FOR ADDRESSING MACHINES

Franklin E. Curtis, Willoughby, Ohio, assignor to
Addressograph-Multigraph Corporation, Cleve-
land, Ohio, a corporation of Delaware

Application May 13, 1938, Serial No. 207,768

28 Claims. (Cl. 101—57)

This invention relates to mechanism for feeding sheets step by step to an addressing machine or other series printing mechanism. The object of my invention is to provide a feeding mechanism which will advance the sheet with great accuracy to the impressing mechanism, enabling the successive imprints to be accurately spaced. The invention is particularly well adapted for feeding sheets where it is desired to list names or other data in regular order, and in definite location with reference to rating or data previously printed on the sheet, as in making up payrolls, tax lists, reports and the like.

Briefly, the invention comprises the combination with impressing mechanism of a movable member adapted to grip the sheet and automatically advance it definite, positively controlled, amounts consequent upon the operation of the machine. More particularly, I combine the controlled feeding operation with a roller feed for the sheet having the possibility of slippage, so that the roller may tend to feed the sheet a slightly different amount from that determined by the controlling device. When so combined, the control device may grip the sheet in front of the impressing mechanism and allow it to be drawn rearward by the roller feeding mechanism definite amounts for each impression.

Controlling the advancing sheet by positive mechanism enables the successive imprints to be printed on transversely ruled sheets and does away with the accumulation of small errors in the roller feed, which ordinarily takes place with a roller feed and results in the successive imprints gradually ceasing to register with the ruled spaces.

The control mechanism can conveniently be an attachment for such addressing machine, as shown and claimed in Patent No. 2,104,747, of C. J. Hueber, issued to my assignee, Addressograph-Multigraph Corporation, though I have improved the wind-up mechanism for the advancing sheet, and the receptacle for discharged plates, illustrated in that patent.

My control mechanism, associated with an address printing mechanism of the Hueber type, is illustrated in the drawings hereof, as hereinafter fully explained in detail.

In the drawings, Fig. 1 is a plan of an address printing machine having my listing mechanism; Fig. 2 is an end view thereof, looking at the right hand end of Fig. 1; Fig. 3 is a vertical section of the line 2—3 on Fig. 2, illustrating, on an enlarged scale, the connection of the listing attachment

chine; Fig. 4 is an enlarged vertical section on the line 4—4 on Fig. 2, illustrating the mechanism periodically advancing the sheet control member; Fig. 5 is a vertical section through the addressing machine; Fig. 6 is a vertical section through the wind-up mechanism of the addressing machine, being on a larger scale and looking in the opposite direction from Fig. 5; Fig. 7 is a detail of the device for advancing the control member, being a vertical section on an enlarged scale on the line 7—7 on Fig. 4; Fig. 8 is a perspective of the feed control member and its co-operating parts; Fig. 9 is a radial section through the friction drive of the take-up roller, as indicated by the line 9—9 on Fig. 1; Fig. 10 is a diagram, illustrating the relation of different interchangeable members for the controlled feed.

It is most convenient to describe first the addressing machine proper, with its frictionally driven take-up device for the advancing sheet, which is illustrated in the drawings; after which I will describe in detail the controlling mechanism which insures the positive feed of the sheet.

As illustrated in Figs. 1, 2 and 5, the machine is shown as having a main frame 10, provided with a horizontal guideway 11, along which printing devices such as address plates A are progressed one after another from the bottom of a stack indicated at 12, to an anvil 13, and thence to a second stack 14. A suitable conveyor is provided to progress the printing devices from one stack to the other. As shown in the drawings, this conveyor comprises feeding pawls 16, carried by a pair of reciprocating feed bars 17, operated by an eccentric 18, which is connected by links 19 and levers 19, to the feed bars. The eccentric 18 is secured to a main shaft 20, journalled in the frame and rotated in suitable manner, as, for instance, by a motor connected through a controllable clutch, not shown.

It will be understood when the feed bars 17 are reciprocated their pawls engage the bottommost printing plate in the stack 12, and other plates which have been previously fed, and carry them toward the right, the plates successively resting in printing position on the anvil 13, and eventually reaching the receiving stack 14.

The platen and the operating mechanism therefore, as illustrated, is more completely described in Patent No. 2,104,863, of C. J. Hueber, assigned to Addressograph-Multigraph Corporation. Briefly, this platen comprises a segmental roller 30, mounted in a reciprocating carriage 31, supported on two spaced frame brackets 32, which extend upwardly and forwardly from the rear of the

machine frame 10 and provide the magazine 12 between the brackets.

As shown, the platen 30 is supported in the platen carriage 31 by a toggle mechanism comprising two pairs of links 34 and 35. A third pair of links 36 guides the movement of the platen, and the angular position of the platen may be controlled by gearing 37 connecting its shaft with a stationary rack 38 on one of the brackets 32.

Any suitable means such as a spring, not shown, may serve to maintain the platen normally in the buckled position shown in Fig. 5. However, when the platen approaches the right-hand end of its idle stroke, the toggle comes into co-action with a suitable abutment, and is thereby straightened and moved into engagement with the work sheet, superimposed over the printing device on the anvil 13.

Following the engagement of the sheet by the platen, the platen carriage moving toward the rear causes the platen to be rolled across the sheet over the printing device, resting on the anvil. A suitable inked ribbon R may be disposed between the printing device and work sheet, thus causing an impression to be made on the under face of the work sheet. As the platen reaches the rear end of its stroke, the toggle is buckled, the platen raised to idle position, where it remains throughout the return stroke to the front.

As shown, the reciprocation of the platen carriage is effected by an eccentric 40, on the shaft 20, connected by a link 41 to a lever 42, which is connected by a link 43 to the platen carriage.

Mechanism is provided for frictionally feeding the sheet and winding up the forward end thereof, following each impression. This mechanism comprises a frictionally driven roller 50, lying within a partial tube 52, located beneath the frame arms 32 at the rear of the platen. This tube, which is the curled rear part of a shield plate 51, is removably secured to the frame 10 by suitable screws, and is open at the lower rear portion of the platen providing an entrance for the sheet into the space between the roller and tube. Friction rolls 53, 54 bear against the roller 50 and press the paper against the latter. I have shown several of these rolls extending through openings in the shield into engagement with the roller 50. These small rolls may be mounted on rods 55, 56, which are mounted in recesses in horseshoe shaped springs 58 about the tube 52.

The roller 50 is frictionally driven in the direction to cause its lower portion to move toward the rear, so that when a work sheet (indicated at P, Fig. 6) is initially positioned with its foremost edge between a set of rolls 53 and the main roller 50, the rotation of the roller 50 will advance the sheet into the space between the roller and shield.

The take-up roller 50 is loosely mounted on a driving shaft 60 journalled in brackets 61 and 62, which are secured to the shield plate 51 by suitable screws such as that shown at 69 in Fig. 3. This shaft, by mechanism hereinafter described, is given a partial rotation following each imprint. Pinned to this shaft is a sleeve 63, Fig. 9, which carries one set of members 64 of a multiple-plate clutch. The alternate members 65 of this clutch are connected to a sleeve 66, which is coupled to the roller 50. Accordingly, the rotations of the shaft 60 are delivered to the roller 50 through the friction clutch. The friction of this clutch is governed by a spring 67, surrounding the sleeve 64, and adjusted by a nut 68.

It will be understood from the description

given that if the record sheet is placed with its forward end in the grip of the take-up roller 50 and the smaller rolls 53, and the machine operated, the platen shaft rolls across the sheet and makes the impression; then, after the platen has been raised clear of the sheet, and is making its back stroke, the roller 50 is given a partial rotation to wind up the sheet sufficiently to bring a proper fresh area of the paper over the anvil, and at the same time the plate feed mechanism is operating to feed forward the line of plates, presenting a fresh plate over the anvil and discharging the foremost plate into the receiving stack. As the plate reaches the forward end of its horizontal movement it drops through an opening in the bed onto a platform 70 pivotally supported by the arms 71 and drawn upward by a light spring 72, the weight of the stack of plates 14 causing the platform to descend gradually as plates are added above it.

The mechanism with which the present invention is primarily concerned coacts with the mechanism for turning the feed roller and, by reason of being gripped to a sheet and fed forward a positively controlled amount, controls advancement of the sheet, the friction clutch 62, 63 allowing slippage of the roller drive as necessary.

The control mechanism will now be described with particular reference to Figs. 1 to 4, inclusive, and 7 and 8. Held on the top face of the frame 10 of the machine, adjacent the right-hand edge, is a guideway 100 shown in cross-section in Fig. 3, having a base 101, upwardly extending side ribs 102 and 103, these side ribs having formed in their inner faces longitudinal recesses 104. In these recesses a bar 105 is slidably mounted. At the forward end of this bar is a clamp, adapted to grip the sheet to be printed.

The paper clamp comprises a laterally extending base portion 108 extending beneath the sheet, (indicated at A, in Fig. 1), and a surmounting clamping member 109, which is pivoted to the base member and spring pressed so that it may grip the sheet.

The paper clamp is mounted on a shim 110 resting on the bar 105 and adapted to pass between the guide arms 102, 103 and extending higher than these arms. This carries the clamp above the top plane of the arm 102 and allows the clamp to pass readily over it. As shown in Fig. 2, the clamping member 109 has down-turned ears 112, which overlap upwardly extending ears 113 on the base member, these ears being pivotally connected by a cross-pin 115.

The clamp is normally maintained active, or in its gripping position, by a spring 116 between the two arms of the clamp back of the pivot. A pin 117 rises from the base member, incidentally positions the spring, passes through an opening in the clamping member and pivotally carries at its upper end a throw-out lever 118 which has differently positioned faces adapted to engage the top of the clamp member 109. When the lever 118 is in the position shown in Figs. 2 and 5, the clamp is active. When the lever inclines toward the front, the face 119 thereof holds the clamp open. The same lever 118 furnishes a convenient handle to draw the clamp toward the front for original setting. As the operator grasps this handle the first action is to open the clamp, if it should be closed, and maintain it open as the clamp is being drawn forward.

The bar 105 forms merely a guide and support for the clamp. The actual advancement of the

clamp is effected by a thin, flexible metal strip 120, which is slideable in the guide 100, the margins of the strip occupying longitudinal grooves 107 in the guide arms 102 and 103. This strip at 5 its forward end is attached by a clamping screw 121 to the guide bar 105.

At its rear end the strip 120 passes into a substantial circular receptacle 125. This receptacle comprises a disk-like plate carrying a nearly 10 completely circular wall 126, the plate having a flanged extension 127 by which it is bolted to the under-side of the projecting rear portion of the guide 100. The wall 126 is open at the top, so that as the strip 120 moves rearwardly it passes 15 into the receptacle and curves around the inner face of the wall.

The strip 120 is intermediately acted upon by periodically moving advance mechanism to move the strip rearwardly a certain amount and thus 20 advance the clamp and with it the sheet of paper following the impression, and at the same time, the strip by means of gearing connecting it with the take-up roller 50, turns that roller to pull the sheet into the shield 52. The feed of the periphery of the roller is slightly in excess of the feed of the clamp and thus the clamp furnishes the 25 actual control for the sheet, the feed roller friction clutch slipping slightly when the roller cannot further advance the sheet. This advancing 30 mechanism will now be described.

The strip 120 has, along its margin, a row of 35 openings 130 into which extend the teeth of a gear 131 (Fig. 3), on a shaft 133 mounted in a bearing block 135, rigid with the frame. As shown, this bearing block is mounted on a plate 152, which extends beneath the guide 100 and is secured to it.

The shaft 133 aligns with and is coupled to the roller shaft 60, each of these two shafts being 40 preferably half cut away and the remaining portions overlapping, as shown in Fig. 3. This makes a positive drive from the strip 120 to the take-up roller shaft 60, and, as there is a positive connection between the strip and the paper clamp, the movement of the strip necessarily turns the 45 roller shaft and moves the strip in unison, and as heretofore stated, the shaft 60 tends to rotate the roller 50 at the same angular speed.

The control strip 120 has another set of holes 40 through it spaced according to the desired feed of the paper. These holes are engaged by reciprocating pawls to effect the feed. As shown in Fig. 1, these holes are arranged in two rows, 140 and 141, the holes being staggered to prevent 45 undue weakening of the strip, and two pawls being provided, either of which may engage a hole to effect the advancement. The two pawls are shown at 142 and 143 in Fig. 1, and one of them is shown in an enlarged scale in Fig. 7. 50 The feeding pawls 142, 143 are pivoted at 144 to a carriage 145, slidably mounted on the guide 100, the carriage having depending bracket portions 146 underhanging ribs on the guide. The 55 pawls are pressed downwardly by springs 147 compressed between them and the top of the carriage. Upwardly projecting pins 148 on the pawls allow them to be raised manually to idle position to enable manual shifting of the strip 120 consequent upon a manual adjustment of the 60 positioning clamps.

The feed pawls are operated by a bell crank lever 150, pivoted at 151 on the depending portion of the plate 152 rigid with the guide 100. The upper end of this bell crank is connected by 65 a link 154 with the pin 144 which is mounted in

the carriage and forms the pivotal mounting for the pawls. The other arm 156 of the bell crank is connected by a link 157 with an arm 158 rigid with the arm 42 (Fig. 5), which operates the platen. Accordingly, when the platen is moved forward on its idle stroke the arm 158 is swung downwardly and this causes the link 154 to move rearwardly, thus giving the pawls a rearward stroke. When either of them engages an opening in the strip 120, the strip and the paper clamp and the take-up roller shaft are advanced 10 corresponding amounts. The stroke is limited by the adjustable set screw 159 on a flange of the bell-crank 150 coming into engagement with the edge of the frame member 152.

The actual advancement of the strip cannot be more than the advancement of the pawls; it may, however, be considerably less, depending upon the point at which the advancing pawls actually engage the strip. This point is controlled by an 20 adjustable shim 160, Figs. 1, 7 and 8, which overlies the strip and prevents the pawls from passing down into the holes in the strip until they have cleared the shim. The forward end of the shim is bevelled, as shown at 161, to enable the 25 advancing pawls to pass gradually off of the shim onto the strip into uncovered holes in the strip, as indicated by the broken lines in Fig. 7.

The effect of the shim, therefore, is to render 30 idle a variable portion of the stroke of the pawls and thus control the amount of feed. The shim is retained in set position by a detent plunger 170 (Figs. 4 and 8), which engages any of the 35 number of notches 162 in the edge of the shim. The plunger has a vertical shank 171 slidably mounted in the bracket 135 and carries at its upper end a knob 172 by which the plunger may be lifted to idle position against the action of a surrounding compression spring 173. When the plunger 170 is raised the shim may be readily 40 shifted by the operator taking hold of a pin 165 as a handle. The shim is preferably provided with a suitable scale coating with a pointer 168 on the guideway 100 to enable the selected 45 position to be readily observed.

In the particular illustration of the strip and 50 shim in Fig. 8, the basis of spacing is $\frac{1}{16}$ "; that is to say, the longitudinal distance from the transverse center line of the hole 140 to the transverse center line of the next hole 141, is $\frac{3}{16}$ ", and the spacing of the notches 162 on the shim is $\frac{1}{16}$ ". Now, if the total stroke of the pawls 142 is $\frac{15}{16}$ ", and the shim is so set as to maintain the pawls idle for the first $\frac{3}{16}$ " of movement, it follows that there is $\frac{1}{16}$ " left for active movement, 55 which corresponds to the longitudinal space from the rear edge of one hole to the rear edge of the third hole thereafter, and thus causes a feed of the strip equal to the distance from the center of one hole 141 to the center of the next hole 141 60 in that row. If, however, the shim were shoved rearward of the machine one notch, the feed would be $\frac{1}{16}$ " less, or $\frac{5}{16}$ ". If, on the other hand, the strip were drawn one notch toward the front the feed would be $\frac{3}{16}$ ".

It will be seen that with the machine equipped 65 with the strip 120 spaced as just described, and the shim set as in Fig. 8, each stroke of the platen results in a feed of the paper of $\frac{1}{16}$ ". Successive imprints may accordingly be equally 70 spaced between the transverse rulings every $\frac{1}{16}$ ", or matter printed by the machine may be presented in accurate transverse alignment with previously printed data spaced $\frac{1}{16}$ ".

To assist in the original placing of the sheet, 75

I put an adjustable pointer 180, Fig. 1, on one of the side guides 181 for the paper on the frame of the machine. When this pointer is once set, it corresponds with some mark on a properly positioned ruled or printed sheet, and every other similarly ruled or printed and marked sheet, which is caused to register with the pointer and will have its ruling or printing correspondingly position with reference to the imprint to be made.

If a spacing of imprints different from any multiple of the hole-spacing of strip 120 is desired, it is only necessary to remove the strip and shim from the machine and substitute a strip with the holes spaced as desired, and a shim which corresponds to the substituted strip. This interchangeability is illustrated in Fig. 10, where the characters 120 and 160 indicate the strip and shim of Fig. 8 while the characters 120a and 160a indicate a strip and shim spaced on a $\frac{1}{4}$ " basis. A few strips with holes differently spaced and corresponding shims will accommodate most of the ordinary rulings of paper, and spacings of printing. If special spacing is desired, it can be easily provided by making a strip and a shim specially to fit a sample of the particularly spaced sheet to be used.

I have referred to the possibility of making the controlled feeding mechanism self-contained as an attachment to the addressing machine. This is the embodiment illustrated in the drawings, wherein the longitudinal guide member 100 constitutes in effect the frame of the attachment. This guide member has rigidly secured to it the bearing for the drive to the take-up roller shaft, the bracket for the pawl-operating mechanism and the receptacle for receiving the free end of the strip. As shown, the guide 100 has near its forward end a downwardly projecting pin 190, which may be placed in a corresponding hole in the machine frame 10; then the whole attachment may be swung about the pin 190 as a center toward the addressing mechanism, causing aligned pins 192 on the stationary frame bracket 45 61 to be received in corresponding openings 193 in the bearing block 135 of the attachment, then the attachment is secured in place by turning in two thumb screws 195 (Figs. 1 and 2), the shanks of which have reduced portions passing through openings in ears on the bearing block 135 into threaded openings in the frame 10, shoulders on these screw shanks engaging the top of the ears.

The simple means described effectively clamps the whole self-contained controlled-feeding mechanism accurately in position with the attachment shaft 133 interlocked to the take-up roller shaft 60. A pin 155 on the link 157 is then caused to pivotally connect that link with the rock arm 158 rigid with the platen operating arm 42. It is convenient to mount the pin 155 in a hollow boss on the link 157 and provide a suitable detent or internal spring not shown, to hold the pin in its innermost position when it is active.

To limit the forward movement of the clamp and retain the strip and clamp guide in place in the guide bar 100, I secure a block 199 to the strip adjacent the rear end. This block by abutting the rear end of the guide 100 limits the forward movement of the strip.

Inasmuch as the paper is set initially according to the ruling or matter on the sheet, and is shoved positively toward the rear, it is very desirable to have means whereby the sheet may pass automatically into the grip of the take-up device 75 without requiring its adjustment manually at

that end. To accomplish this, I provide guide strips 80 secured to a cross-bar 81 attached to the bearing brackets 61 and 62, these guide strips being bifurcated, and passing forwardly and thence downwardly on opposite sides of the rolls 53 to points below the upper face of the shield, as shown in Figs. 1 and 6. With such provision, when the sheet P is fed rearward by the clamp feed the far edge of the sheet strikes the upwardly inclined face of the strips 80 and thus pass immediately into the bight of the roller 50 and the rolls 53 without requiring manual manipulation at the rear end.

As the sheet of paper is held at the front of the machine by the clamp and at the rear of the 15 platen by the take-up roller and intermediately overlies the chamber in which the used plates are stacked, it is desirable that means be provided whereby those plates can be removed, when the stack becomes full, otherwise than by raising the 20 stack through the top plane of the frame, as heretofore. To accomplish this I make the side-walls 90 of the receiving receptacle continue unobstructed to the front, except for lugs 91 at the top. The result is that as the foremost used plate is 25 fed, its far edge abuts the shoulders 90 and is thereby limited in forward movement and drops by gravity onto the platform 70 or onto the plates already on the platform. The platform inclines upwardly, as shown in Fig. 5, and hence gravity 30 assists in retaining the stack of plates against the rear face of the chamber provided for receiving them. However, whenever desired, the operator may insert his fingers into the open chamber beneath the paper sheet and grasp and 35 remove plates resting on the platform, the platform having a central opening to allow the plates to be readily grasped.

It will be understood from the description given that I have provided a positively driven paper feed mechanism, self-contained as a unit, and adapted to be installed on an addressing machine and then operating to feed the sheet by definite steps and correspondingly roll up the advancing edge of said sheet. I have provided for ready interchangeability of the controlling members to 40 enable step feeds of different amounts. I have provided a ready adjustment within the machine to enable the mechanism to cause a feed of the selected amount or any multiple thereof, as desired. I have so arranged my positive feeding mechanism which grasps the sheet at the front and the take-up mechanism which receives the rear edge of the sheet, that the paper clamped by the positive feed may be readily shoved into the 45 automatic grip of the wind-up mechanism. Finally, I have so modified the plate-receiving magazine that used plates may be readily removed, notwithstanding a sheet of paper may be held in a plane across the top of the magazine.

I claim:

1. The combination with means for impressing a sheet, a clamp for holding a sheet to be impressed, said clamp being carried by a bar slidably mounted in a guide carried by the frame which carries the impressing mechanism, a removable strip slidably mounted in a guide parallel with the bar-guide and adapted to be attached to the bar, said strip having periodically arranged shoulders, and feeding mechanism 70 adapted to engage such shoulders.

2. The combination with mechanism adapted to impress a sheet, a flexible strip connected to the sheet and having a series of longitudinally spaced shoulders, means adapted to engage the 75

shoulders successively to advance the sheet, and means for curling the distant end of the flexible strip.

3. The combination with mechanism adapted to impress a sheet, of a clamp for holding the sheet, said clamp being slidably guided, a flexible strip connected to the clamp and having a series of longitudinally spaced shoulders, means adapted to engage the shoulders successively to advance the strip and thereby the clamp, and means for curling the distant end of the flexible strip.

4. The combination with means for impressing a sheet, a movable clamp for holding a sheet to be impressed, a flexible strip slidably guided and connected at one end to the clamp, said strip having shoulders periodically arranged along it, and feeding mechanism adapted to engage such shoulders, and a receptacle having a curved wall to receive the free end of the strip.

20. 5. The combination with a printing mechanism, of a paper holding device slidably mounted, a thin flexible strip slidably guided at its edges and connected with the paper holding device, said strip having a longitudinal row of holes 25 through it and a feeding device adapted to engage different holes in the strip successively to give the strip a step-by-step movement.

6. The combination with a printing couple, of a device for holding a sheet of paper to be imprinted, said device being slidably guided on the frame of the machine, a slidably guided strip adapted to be attached to the holding device, said strip having a plurality of rows of holes through it, the holes being staggered in adjacent rows, and reciprocable feeding devices adapted to coat with holes in any row, to advance the strip.

7. The combination of a frame, a printing couple mounted thereon, a paper clamp for a sheet to be printed carried by a bar slidably mounted in a guide carried by said frame, a strip slidably mounted to move parallel to said bar, said strip having a set of equally spaced shoulders, a reciprocable driving pawl having a stroke as great as a plurality of distances between said shoulders, and an adjustably positioned member adapted to prevent the pawl coating with the strip for a portion of its stroke.

8. The combination, with a printing couple, of a paper holding device slidably guided to present a sheet successively to the couple, a slidably mounted strip attached to the paper holding device and having a set of holes in it, a reciprocable pawl adapted to engage holes in the strip to feed the same, and an adjustable shim overlying the strip and adapted to prevent such engagement for a portion of the stroke of the pawl.

9. The combination, with a printing couple, of a paper holding device slidably guided to present a sheet successively to the couple, a slidably mounted strip attached to the paper holding device having a row of shoulders, a reciprocable pawl adapted to such shoulders to feed the paper holder, an adjustable shim adjacent the strip and adapted to prevent such engagement for a portion of the stroke of the pawl, said shim having a set of shoulders thereon, and a spring detent device adapted to engage any of said shoulders on the shim and thereby hold the shim in adjusted position while allowing it to be shifted lengthwise of the strip as desired.

70. 10. The combination of a printing couple, a pair of coating takeup rollers adapted to feed a sheet between the members of the couple, a clamp to engage such sheet, and means for feeding the clamp periodically definite steps.

11. The combination of a printing couple, a pair of coating takeup rollers adapted to engage and pull a sheet between the members of the couple, a clamp to engage such sheet, on the other side of the couple, and means for feeding the clamp periodically definite steps to control the feed.

12. The combination with means for feeding a set of address plates to printing position, a platen adapted to coat with a plate in printing position to effect an imprint, a paper-feeding roller, means for rotating it, a clamp for the sheet slidably mounted, and mechanism for periodically moving the clamp by positively controlled amounts at the same time that the roller is rotated in engagement with the sheet.

13. The combination, with a printing couple of a roller feed for the sheet, a movable clamp adapted to grip the sheet, and mechanism to advance the clamp by definitely controlled steps 20 and simultaneously rotate the feed roller in a manner which would feed the sheet greater amounts than said steps if the clamp permitted the same.

14. The combination with a printing couple, 25 of a positively advanced controlling device adapted to be clamped to the sheet to be printed, and a wind-up mechanism simultaneously operated to receive the printed sheet.

15. The combination with means for feeding 30 a set of address plates to printing position, a platen adapted to coat with a plate in printing position to effect an imprint, a takeup roller behind the platen, a rolling member coating with the take-up roller to engage the sheet between 35 them, a clamp for the sheet slidably mounted in front of the platen, and mechanism for periodically moving the clamp toward the impressing position by positively controlled amounts and at the same time operating the takeup roller is rotated to wind up the sheet.

16. The combination with a printing couple, of a frictionally driven paper feed mechanism, and a positively advanced controlling device adapted to be clamped to the sheet to be printed.

17. The combination with a printing couple, of a feed roller, means holding the sheet being imprinted against the feed roller, means for frictionally driving the feed roller, a clamp adapted to engage the sheet, said clamp being guided for movement in the plane of the sheet, and mechanism to advance the clamp by definitely controlled steps.

18. The combination, with a printing couple of a roller feed for the sheet, mechanism for driving the roller feed, a movable clamp adapted to grip the sheet, mechanism to advance the clamp by definitely controlled steps and simultaneously operate the drive mechanism for the roller feed, said drive mechanism including a 55 slip connection whereby the roller feed may tend to feed the sheet further than the clamp will allow.

19. The combination of means for feeding a sheet of address plates to printing position, a 65 platen adapted to coat with a plate while in printing position, a clamp adapted to grip a sheet to be impressed, a takeup roller adapted to roll up the impressed sheet, and mechanism operating in timed relation with the platen while the latter is idle to positively advance the clamp and frictionally advance the takeup roller.

20. The combination of a printing couple, a rotatable takeup roller and a coating member adapted to receive between them the impressed 75

sheet, a gear frictionally connected with the roller for rotating it, a movable clamp adapted to grip the sheet, a member movable with the clamp and having shoulders meshing with the gear, and 5 mechanism for feeding said member a definite amount for each impressing operation.

21. The combination of mechanism for feeding address plates, one after another, to printing position, a platen adapted to be moved to coact 10 with a plate in printing position, a takeup roller having a roll coacting with it to receive between them the sheet impressed, a clamp adapted to be attached to said sheet, a bar slidably guiding the clamp, a strip removably connected to the 15 clamp and having a set of equally spaced shoulders, a reciprocating pawl to engage such shoulders to feed the strip and thereby feed the clamp, and a gear engaging the strip and connected to the takeup roller through a friction drive, where- 20 by reciprocation of the pawl may both rotate the feed roller and advance the clamp positively, the gearing to the feed roller being such that it tends to advance the sheet further than the clamp will allow.

25. 22. The combination with a printing couple, of a takeup device for a sheet including a rotatable roller, a slidably mounted clamp adapted to engage the sheet, a thin flexible strip connected to the clamp and slidably guided, said strip hav- 30 ing a row of holes through it coacting with teeth on a gear frictionally connected with the takeup roller, said strip having another row of holes through it, a reciprocating pawl adapted to coact with the holes of the latter row to feed the 35 strip definite amounts, whereby the clamp is advanced positively and at the same time the takeup roller is advanced frictionally.

23. A paper advance device, comprising a clamp adapted to engage the sheet, a bar slidably guid- 40 ing the clamp, a strip connected to the clamp, said strip having a plurality of rows of openings through it, the openings in one row being staggered with reference to the adjacent row, a slide- 45 able carriage, a plurality of pawls on the carriage adapted to coact individually with the openings in the different rows and means for reciprocating the carriage whereby as soon as either pawl engages a hole in its row the strip becomes advanced by such pawl.

50. 24. The combination, with a printing couple, of a takeup device for the impressed sheet comprising a roller, a shield extending from the region beneath the sheet and curving about the roller but spaced therefrom, a roll coacting with the roller at the rear of the roller, a guiding strip extending forwardly and downwardly through a rear opening in the shield, and means for positively gripping the sheet and shoving it rearwardly with the free end traveling along said strip 55 and directed by it into the bite of the feed roller and coacting roll.

25. In an addressing machine, the combina-

tion of a frame, means thereon for supporting a stack of address plates, means for feeding them across an anvil, a platen adapted to coact with a plate on the anvil, means including a clamp in front of the machine-frame for gripping a sheet 5 of paper and positively feeding it across the anvil while holding it in a plane overlying the path of travel of the plates from the anvil, and a yieldable support for receiving the discharged plates, said support occupying a chamber open at the 10 front of the machine for the full width of the plates, whereby the stack of plates may be readily removed from the front of the machine while the sheet of paper is in place above the receiving chamber.

26. A printing machine of the character de- 15 scribed, having a frame, a magazine for holding plates to be printed, a second magazine for receiving plates which have been printed, mech- 20 anism for feeding the plates from the first mag- azine to the second and intermediately locating them over an anvil, a platen adapted to coact with a plate on the anvil, a takeup device be- 25 tween the platen and the first magazine comprising a roller mounted within a curved shield, and a roll projecting through an opening in the shield into coaction with the roller, a bar slidably mounted in a frame in the machine, a clamp on the bar, means for opening the clamp and for closing it on the paper to be printed, a remov- 30 able flexible strip secured to the clamp and ex- tending parallel with the bar and having its far end curled into a receptacle at the rear of the machine, said strip having a row of holes through it, a pawl reciprocating parallel with the strip 35 adapted to engage different holes to advance the strip, a shaft for the takeup roller connected with it through a slip clutch, a gear connected with said shaft and coacting with a row of holes in the flexible strip, mechanism for moving the 40 platen and on the idle stroke thereof advancing the pawl to advance the clamp positively and advance the takeup roller frictionally.

27. The combination with a printing mech- 45 anism, of a paper holding device slidably mount- ed, a thin flexible strip slidably guided and con- nected at one end with the paper holding device, said strip having a longitudinal row of holes through it, and a reciprocating pawl adapted to engage different holes in an intermediate portion 50 of the strip successively to give the strip a step- by-step movement, and means for diverting the advance end of the strip.

28. The combination of a printing couple, a 55 device adapted to advance a sheet step-by-step approximately identical amounts while allowing variations, a paper controlling device adapted to be clamped to the sheet, and means for positively feeding the paper controlling device step- 60 by-step identical amounts while the first men- tioned device is active.

FRANKLIN E. CURTIS.
